UNITED STATES PATENT OFFICE.

FREDERICK A. HEAD, OF ROCK ISLAND, ILLINOIS.

WHEEL-PLOW.

SPECIFICATION forming part of Letters Patent No. 391,047, dated October 16, 1888.

Application filed July 28, 1888. Serial No. 281,329. (No model.)

To all whom it may concern:

Be it known that I, FREDERICK A. HEAD, residing at Rock Island, in the county of Rock Island and State of Illinois, and a citizen of the United States, have invented a new and useful Improvement in Wheel-Plows, of which the following is a specification, reference being had to the accompanying drawings, in which—

Figure 1 is a plan. Fig. 2 is a side elevation, one wheel and part of the axle being removed. Fig. 3 is a detail, being a front view of a portion of the axle and an arm thereon. Fig. 4 is a modification, being a side elevation of the parts shown. Fig. 5 is a modification, 15 being a plan of the parts shown. Fig. 6 shows my improvement applied to a crank-axle, so arranged that the wheels are forward of the main horizontal part of the axle, instead of behind the same, as shown in Fig. 1; and this 20 figure is a side elevation, one wheel and part of the axle being removed.

This improvement relates to wheel-plows which are provided with crank-axes.

The object of my invention is to so construct 25 a wheel-plow which has a crank-axle that the power of the team will assist the operator in raising the plow, which I accomplish as illustrated in the drawings and hereinafter described.

30 That which I claim as new will be pointed out in the claim.

In the drawings, A represents a crank-axle. B B represent the wheels.

C D are two plow-beams, connected with the 35 bent axle in any suitable manner and each adapted to receive a plow, as is common in gang-plows.

a is an arm or downward extension from the 40 axle A, and is permanently secured thereto. b is a draft-rod, one end of which is connected with the arm a and the other end is provided with a hook or other device, to which an evener may be attached. When two beams

45 are used, the forward end of this draft-rod b may pass between two short bars which are attached to the forward ends of the beams C D, and the position of the draft-rod between these two short bars may be adjusted so as to be either at the center or to one side thereof, 50 for the purpose of changing the line of draft, if desired.

The plows are to be provided with a suitable lever or levers and a rack or racks for the purposes of raising and lowering the plows and holding the same in the adjusted position, 55 as is usual. In use the tendency of the draft of the team through the draft-rod b, connected, as described, with the arm a, will be to rock the crank-axle, and, as the wheels move forward, to raise the central part of the axle and 60 the plow; but the construction is such that the draft of the team will not lift the plow out of the ground and keep it constantly raised, but will partly counterbalance it when in use, and hence the operator can easily raise the plow 65 by means of the usual lever. The same object can be accomplished in other ways which are substantially the same as I have described.

In Fig. 4 I have shown one modification, 70 in which c represents an arm extending upward from the axle, instead of downward. d is a lever pivoted to a plow-beam, or between two plow-beams when two are used, one arm of which extends above and the other below such beam. e is a bar pivoted to the upper ends 75 of the arm c and lever d. f is a draft-rod corresponding to the draft-rod b and connected with the lower end of the lever d. With this modification the operation is the same as before described, the tendency of the power of the team being to raise the plow through the lever d, connecting-arm e, and arm c.

In Fig. 5 I have shown another modification, in which there are two draft-rods, g h. The inner end of the draft-rod g is connected 85 with the inclined part i of the bent axle, and the inner end of the other draft-rod is connected with the inclined portion j of the bent axle at a little distance from the point where these bent portions join the central horizontal 90 part of the axle. With this modification the action of the team on the axle through the draft-rods g h has a tendency to raise the plow in the same manner as before described.

Wheeled plows are sometimes provided with 95 crank-axes so arranged that the wheels are forward of the central horizontal part of the axle, instead of behind the same. In such plows the desired result is obtained by attaching an arm which extends upward from the 100 axle, as illustrated in Fig. 6, in which k represents an arm rigidly secured to the central

part of the axle, which arm extends upward, and the office of which arm is the same as that of *a* in Fig. 2. *l* in this Fig. 6 is the draft-rod, corresponding in office with the draft-rod *b* in Fig. 2. With this construction the power of the team has a tendency to raise the plow.

My improvement is adapted to be used in connection with a single plow as well as gang-plows, no material change in construction being required.

What I claim as new, and desire to secure by Letters Patent, is as follows:

In a wheel-plow, a bent or crank axle, in combination with one or more draft-rods connected with the axle or with an arm or arms on the axle, substantially as set forth, whereby the draft of the team will have a tendency to raise the central part of the axle and the plow, substantially as specified.

FREDERICK A. HEAD.
